IGNITION CONTROLLING APPARATUS

Filed May 23, 1924

Inventor,
Alonzo Howard
By Charles J. Schmidt
Atty.

UNITED STATES PATENT OFFICE.

ALONZO HOWARD, OF CHICAGO, ILLINOIS.

IGNITION-CONTROLLING APPARATUS.

Application filed May 23, 1924. Serial No. 715,397.

To all whom it may concern:

Be it known that I, ALONZO HOWARD, a citizen of the United States, and a resident of Chicago, in the county of Cook and State of Illinois, have invented certain new and useful Improvements in Ignition-Controlling Apparatus.

My invention relates to ignition controlling apparatus particularly for Ford engines and the object is to provide simple mechanism and arrangement for insuring at least one highly efficient spark for each gas charge in each cylinder when the engine is running at slow speed, and to insure a series of distinct, highly efficient sparks for each gas charge in each cylinder when the engine is running at higher speeds, so that the engine can be readily and quickly started and will operate efficiently on very low speed and will operate with certainty and with greater efficiency at any speed.

In the operation of Ford engines several conditions must be met before reliable and efficient sparking can be obtained under all conditions of speed and operation. In Ford multipolar magnetos as now constructed there are sixteen poles whose coils are connected in series to secure the necessary potential. There are eight periods per revolution when the current is of positive polarity and eight periods when it is of negative polarity, or sixteen alternations per revolution. The cam shaft traveling one half as fast as the engine shaft, the primary side of the ignition circuit will therefore receive thirty-two alternations per revolution of the crank shaft, sixteen positive and sixteen negative. To get sufficient sparking potential, the current at the time of sparking must be taken from at or sufficiently close to the high potential sections or peaks of the current wave. Now at slow speed, the current curve is quite sharp or peaked and therefore allows only a small and limited range where sufficient potential is available for proper sparking. This is one condition that must be met. Of course, when the speed increases the curve flattens or bulges correspondingly and gives greater sparking range.

Another condition to be met, particularly when a battery is used, is that the primary side of the induction coil requires a certain length of time to become sufficiently sat-

urated to cause the induction of secondary current of sufficient strength to give an efficient spark.

Another condition to be met is in connection with the mechanical operation of the circuit breakers particularly where springs are used. Owing to momentum and inertia, such circuit breakers require time to arrive at proper circuit opening or circuit closing positions and conditions.

Sufficient travel of the circuit breaking controlling cam element must therefore be allowed after each operation in order that the circuit breakers may get into proper working condition and in order that the induction coil may function properly electrically and magnetically.

On account of the limited potential range at slow speed, it has been difficult to get proper timing and sparking particularly, when adjustment is made to advance or retard the spark. In some prior arrangements devised to eliminate the electromagnetic vibrator of the original Ford system, sets of teeth or other cam formations are provided for cooperating with a circuit breaker in the hope that during each series of operations of the circuit breaker at least one break of the primary circuit will be timed with a sufficiently high potential section of the alternating current wave. Such arrangement might operate during slow speed of the engine, but with increased speed, on account of the teeth or cam formations being so close together, it is impossible for the induction coil to recover its inducing strength after each operation sufficiently to give a proper spark, and the inertia of the circuit breaker parts will interfere, so that there is no certainty nor efficiency in the sparking. An arrangement like the one referred to is disclosed in Smith Patent 1,403,203 of January 10, 1922.

In another arrangement of the prior art as disclosed in Snell 1,164,317 of December 14, 1915, the cam member has thirty-two teeth spaced equally apart and corresponding in number with the alterations of the magneto current. With this arrangement special commutator mechanism is necessary to take care of the advancing or retarding of the sparking period at the engine. I have also found that in such arrangement the interval between openings of the pri-

mary circuit is not sufficiently great, particularly at high speed, to permit recovery of the induction coil or the breaker parts.

In accordance with my invention, I provide for a series of cooperations between the cam member and circuit breaker mechanism for the ignition period of each cylinder, the circuit breaker mechanism being normally open and the closure intervals between its 10 openings being of sufficient length to permit proper recovery of the induction coil and the circuit breaker mechanism, and I have found that better results may be obtained by having the intervals of different 15 lengths. I have found that with three actuations of the circuit breaker mechanism, with the interval between the first and second breaks fifteen degrees and that between the second and third breaks thirteen degrees, 20 certain and efficient sparking is assured at the lowest speed as well as at any other speed up to the highest, and that at slow speed at least one high potential spark will be produced while at higher speeds three 25 distinct efficient and high potential sparks will be produced for each gas charge in a cylinder.

On the accompanying drawing, I show mechanism for carrying out my invention 30 and its operation. On the drawing—

Fig. 1 is a side elevational view of the circuit controlling apparatus,

Fig. 2 is an inner side view of the distributor,

Fig. 3 is a front elevational view of the circuit controlling mechanism housing with the distributor head removed,

Fig. 4 is a view similar to Fig. 3 showing a modified arrangement of circuit breaker mechanism,

Fig. 5 shows a modified arrangement of cam formation, and

Fig. 6 is a diagram showing the circuit connections.

On the drawing F represents the frame of an engine to which the controlling apparatus is applied and C represents the crank shaft of the engine. The housing A of the apparatus rotatably seats in the frame F 50 and the cam shaft extends through the rear wall of the housing into the interior thereof of where it receives the hub 10 of the cam member, such hub being detachably held to the shaft by a key 11. From the inner end 55 of the cam member hub extends the cylindrical cam flange 12 which in its periphery has groups of cam formations designated as a whole, a, b, c, and d, there being four groups as the apparatus shown is designed

for a Ford engine which has four cylinders. The cam formations shown are in the form of notches or depressions a¹, a², a³, b¹, b², b³, c¹, c², c³, d¹, d², d³, respectively, for the four groups. As will be explained more fully later, these notches correspond with

the closure period of the primary circuit controllers, while the cylindrical parts of the cam flange correspond with the opening periods of such circuit controllers. The circuit controllers are designated as a whole by 70 S and are arranged within the housing A between its cylindrical wall and the notched periphery of the cam flange.

Each circuit controller comprises a lever 13 pivoted at one end on a post 14 secured to 75 the back wall of the housing A. Intermediate its ends the lever has a cam tooth 15 for cooperating with the cam flange periphery and notches, a spring 16 extending between the free end of the lever and a post 17 tending to hold the tooth against the cam flange to accurately follow its contour as the cam member is rapidly rotated with the cam shaft. A Z-shaped bracket 18 is secured on the lever 13 and its overhanging 80 end carries a contact point 19 which cooperates with the contact point 20 on the lower flange of a U-shaped bracket 21 which is secured against the inner face of the cylindrical wall of the housing A but is insulated 85 therefrom in any suitable manner. From this bracket 21 a threaded stem 22 extends through the cylindrical wall of the housing A and is received by the clamping nut 23, and also has the knurled nut 24 between 90 which and the clamping nut connection is made with the primary circuit of the induction coil. When the cam tooth 15 is in engagement with the cylindrical surface of the cam flange, the lever 13 will be raised and the contact points 19 and 20 will be separated, and when the tooth engages in one 95 of the notches or depressions the contact points will be brought into engagement, the primary circuit being thus open and closed 100 105 for definite periods of time.

The main result to be arrived at with my improved apparatus is the production of a series of distinct sparks for each gas charge in each cylinder and to insure that at least one of such sparks will be highly efficient, particularly when the engine is running at low speed. In my Patent No. 1,466,720 of September 4, 1923, I show mechanism comprising two circuit controllers, each of 110 which independently controls the formation of one of the sparks of a series, and ample time is given the circuit controllers to fully recover from inertia and other effects before being again put into operation. In my pending application Serial No. 673,904 filed November 10, 1923, I show three circuit controllers in order to increase the chances of at least one of the circuit controllers operating along the high potential sections of the 115 magneto current wave. In the arrangement of this copending application, the interval between the operation of the first controller and the second is the same as the interval 120 between the operation of the second controller and the third. In the apparatus shown, the 125 interval between the operation of the first controller and the second is the same as the interval between the operation of the second controller and the third. The 130

troller and the third. I have found that by making the intervals between the operations of the primary circuit different and having such intervals of sufficient duration to permit full magnetic and inertia recovery, at least one powerful spark is produced during each gas charge in a cylinder at a speed less than the starting speed of the engine which is approximately one hundred and fifty-two revolutions per minute, and at higher speed each circuit controller will produce a powerful spark so that at such higher speed a series of powerful distinct sparks will be assured for each gas charge in a cylinder. I have found that an interval of fifteen degrees between the first and second openings of the primary circuit, and an interval of thirteen degrees between the second and third openings of the primary circuit gives very satisfactory and efficient results, the intervals referred to being the degrees of rotation of the cam member 12. In the curve of a Ford engine there are thirty-two alternations per revolution of the crank shaft so that each positive and each negative section of the curve is of eleven and one-quarter degrees extent. The intervals fifteen degrees and thirteen degrees between the first and second and second and third operations of the primary circuit are each greater than this extent of the curve section but such increased interval is necessary in order to permit magnetic and inertia recovery of the induction coil and the circuit controllers, respectively.

In the arrangement shown in Fig. 3 of the drawing, I show a single circuit controller for the primary circuit and the four groups of cam formations referred to hereinbefore for consecutively cooperating with the circuit controller to produce a series of distinct sparks in each cylinder for each gas charge therein. The depressions a^2 and a^3 correspond with the operation intervals fifteen degrees and thirteen degrees, and in advance of these depressions is the depression a^1 which is preferably longer, say from eighteen to twenty degrees. As shown the cam member rotates in the direction of the arrow and the cam tooth 15 is just in advance of the first depression a^1 of the cam formation group a , the circuit controller lever 13 being raised to separate the contacts 19 and 20 to thus hold the primary circuit open. As the cam member rotates, the cam tooth will drop into the depression a^1 and the primary circuit will be closed. Such long depression is particularly desirable where a battery is used, as it will then give the battery ample time to fully charge the primary side of the induction coil. At the end of the depression a^1 the cam tooth will be engaged by the cam periphery section t^1 and the contact points will be reopened and the primary circuit broken so that a charge

of secondary current will flow through the sparking circuit as will be described more fully hereinafter. After such opening the cam tooth drops into the depression a^2 and the primary circuit is again closed until the cam periphery section t^2 is reached, when the circuit will be again opened and a second charge of secondary current produced. The cam tooth then drops into the depression a^3 until the advance end of the cam periphery section t^3 is encountered when the primary circuit will again be opened and a third flow of secondary current produced. During each flow of secondary current a spark will be produced at the plug for the cylinder of the engine corresponding with the respective cam formation groups a , b , c , or d . The group a controls the sparking for the cylinder No. 1 and the group b for cylinder No. 2, etc. Three distinct sparks are thus produced in each cylinder for each gas charge therein.

Where a single circuit controller is used as in the arrangement of Fig. 6 it must perform many operations particularly at high speeds, and under some conditions it may be desirable to distribute the control of the primary circuit between three circuit controllers s^1 , s^2 , and s^3 , shown in Fig. 4. The cam flange 12 has four depressions e^1 , e^2 , e^3 , and e^4 , in its periphery spaced ninety degrees apart and of say thirteen degrees extent. This will give the raising points p^1 , p^2 , p^3 , and p^4 spaced ninety degrees apart, for cooperating with the cam teeth 15 of the respective circuit controllers to effect reopening of the primary circuit after a period of closure thereof while the cam teeth engage in the depressions e^1 , e^2 , e^3 or e^4 . The circuit controllers are, however, circumferentially offset with reference to the depressions and raise points, the controller s^2 being set so that its cam tooth 15 will be engaged by the raise point p^2 fifteen degrees after the cam tooth of the controller s^1 was engaged by the raise point p^1 , and the controller s^3 is set so that its cam tooth will be engaged by the raise point p^3 thirteen degrees after the cam tooth of the controller s^2 has been engaged by the raise point p^2 . This will give the interval of operation between the controllers s^1 , and s^2 , of fifteen degrees and between the controllers s^2 and s^3 of thirteen degrees, giving the same results as with the arrangement of Fig. 6 so far as the sparking is concerned. The depressions are of sufficient extent to insure long enough closures of the primary circuit before the opening thereof to permit saturation of the induction coil and full mechanical recovery of the circuit controllers. The unequal intervals (shown as fifteen degrees and thirteen degrees) between the operations of the first and second controllers and the second and third controllers

respectively, will insure that at least one of the controllers will operate along a high potential section of the magneto wave, particularly during slow speed of the engine.

5 The long depressions of primary circuit closure periods shown in Fig. 6 are very important, particularly where direct current battery is used, as with such current it requires more time for the induction coil to 10 become properly saturated. With alternating currents less time is required and when a generator is used, the depressions a^2 , a^3 , b^2 , b^3 , etc. may be shortened as shown in Fig. 15. The raise points t^1 , t^2 , t^3 , will, however, maintain their spacing, namely fifteen degrees and thirteen degrees, so that whether 20 battery or magneto is used, the circuit controllers will be given ample time to fully recover from inertia and other effects after 25 operation thereof, and when magneto is used openings of the primary circuit will occur at sufficiently high potential points of the current wave. By shortening the depressions the raise sections t^1 and t^2 will also be given more material so that they may better resist wear when they engage with the cam teeth of the circuit controllers.

Referring to Figs. 1 and 2 the distributor head H is concentric with the housing A and has the central chamber 25 for receiving the hub 10 of the cam member. On the cam member is mounted the secondary current distributor brush 26 whose inner end is opposite to the center or lead-in segment 27 in the head. The outer end 26' of the distributor brush travels past the inner ends of the distributor segments 28, these segments leading to sockets 29 in the head where they are connected with the conductors leading 30 to the various spark plugs of the engine. The lead-in segment 27 extends to the socket 30 for connection with one terminal of the secondary winding of the induction coil. In Fig. 5 I diagrammatically show the induction coil, the cam circuit controller mechanism and the distributor mechanism, and the electrical connection between them. The primary winding 31 of the induction coil has one terminal connected through conductor 32 with the contact 20, the other terminal of the coil being connected with conductor 33 to which may be connected the magneto M or the battery B, the magneto being shown connected. The other terminals of the magneto and battery are connected with ground. One terminal of the secondary winding 34 of the induction coil is connected with ground and the other terminal is connected by conductor 35 with the center segment 27 of the distributor mechanism. The other segments 28 are connected by conductors 36, 37, 38 and 39 with the various spark plugs α if the cylinders No. 1, No. 2, No. 3 and No. 4 of the engine, the other terminals of the plugs being con-

nected through conductor 40 with ground. The contact lever 13 of the circuit controller mechanism is connected with ground through conductor 41. In the position shown, which is the same as that in Fig. 3, 70 the cam formation group a is about to cooperate with the circuit controller s and the primary circuit will be closed and reopened three times while the distributor brush 26 is traveling past the distributor segment 28 connected with the spark plug of cylinder No. 1 and three distinct sparks will be given in cylinder No. 1 for the explosive gas charge therein. The cam formation group b will next cooperate with the circuit controller while the distributor brush is traveling past the segment connected with the spark plug in cylinder No. 2 and three distinct sparks will be given in that cylinder. The spark plug of cylinder No. 4 will next be 80 served and then that of cylinder No. 3. After each opening of the primary circuit and induced sparking current flow through the secondary circuit the primary circuit will be closed a sufficient length of time to permit 85 full magnetic saturation of the induction coil and full recovery of the circuit controller, so that the circuit controller will have come fully to rest and in proper condition to function to reopen the primary circuit. The intervals between the operations 90 of the circuit controller for each group of cam formations being unequal and the length of the intervals being each greater 95 than the duration of a wave alternation, the sparks of each series will develop from a sufficiently high potential point on the curve to insure a perfect, efficient ignition 100 spark, even when the engine is running at low speed, and throughout the entire range 105 of adjustment for advancing or retarding the sparking.

With the arrangement of the three circuit controllers shown in Fig. 4 the three binding posts for the terminal points 20 would be connected together and with the primary winding, and the levers 13 which support the contact points 19 would be grounded. The controller S^1 will be operated first by the raise point p^1 to open the primary circuit after a period of closure thereof along the depression t^1 , and the first spark will be given in cylinder No. 1. After 15 degrees of rotation of the cam member controller S^2 will be reopened by raise point p^2 and the second spark will be given in cylinder No. 1. Then after 13 more degrees of rotation of the cam member controller S^3 will be reopened by the raise point p^3 and the third spark will be given in cylinder No. 1. Cylinders Nos. 2, 4 and 3 will then be successively served, each with three distinct sparks. Thus with either the single controller shown in Fig. 3, or the three controllers shown in Fig. 4, each cylinder will be served with 110 115 120 125 130

three distinct sparks for each gas charge or ignition period and with the different time intervals between sparks referred to. By using three controllers, each will perform only one third as many operations as the one controller in the arrangement of Fig. 3, and the wear and tear will be correspondingly less.

10 I do not desire to be limited to the exact construction, arrangement and operation shown and described, as modifications may be made which will still come within the scope of the invention.

15 I claim as follows:

- 15 1. In an ignition system the combination of inductively related primary and secondary circuits, a spark plug connected in the secondary circuit, a source of alternating current for the primary circuit, circuit controlling mechanism for said primary circuit, and means for causing three or more operations of said circuit controller mechanism during each ignition period of the engine with which said spark plug is associated, each operation controlling the primary circuit to cause a flow of secondary current and a spark at the spark plug whereby a series of distinct sparks is caused at the spark plug during each ignition period, the time intervals between the sparks being different.

20 2. In an ignition system, the combination of inductively related primary and secondary circuits, a spark plug connected in the secondary circuit, a source of alternating current for the primary circuit, circuit controlling mechanism for said primary circuit, and means for controlling the operation of said circuit controller mechanism to cause more than two distinct interruptions of the primary circuit during each ignition period of the engine with which said spark plug is associated, whereby a series of sparks will be produced at the spark plug during each ignition period, the time intervals between said interruptions being each greater than the alternation duration of the current flow from said alternating current source.

25 3. In an ignition system, the combination of inductively related primary and secondary circuits, a spark plug connected in the secondary circuit, a source of alternating current for the primary circuit, circuit controller mechanism for the primary circuit, and means cooperating with said circuit controller mechanism to cause more than two distinct interruptions of the primary circuit for each ignition period of the engine with which the spark plug is associated, each interruption of the primary circuit causing a flow of secondary current and a spark at the spark plug whereby a plurality of distinct sparks is caused at said plug during each ignition period, the intervals between the interruptions differing from each other and each being of greater duration than the

30 mechanism during each ignition period of the engine with which the spark plug is associated whereby a plurality of distinct successive sparks will be produced at said spark plug during each ignition period, the intervals between said operation being each of greater duration than the alternation period of the current from said source.

35 4. In an ignition system the combination of inductively related primary and secondary circuits, a spark plug connected with the secondary circuit, a source of alternating current for the primary circuit, circuit controller mechanism for said primary circuit normally holding said circuit open, and means for causing a succession of operations of said circuit controller mechanism during each ignition period of the engine with which the spark plug is associated, each operation causing a short closure of the primary circuit and reopening thereof to cause induced current flow through the secondary circuit and said spark plug whereby a plurality of distinct sparks is caused at said plug during each ignition period, the intervals between reopenings of said primary circuit being each greater than the alternation period of the current of said source.

40 5. In an ignition system the combination of inductively related primary and secondary circuits, a spark plug connected with the secondary circuit, a source of alternating current for the primary circuit, circuit controller mechanism for said primary circuit normally holding said circuit open, and means for causing a succession of operations of said circuit controller mechanism during each ignition period of the engine with which the spark plug is associated, each operation causing a short closure of the primary circuit and reopening thereof to cause induced current flow through the secondary circuit and said spark plug whereby a plurality of distinct sparks is caused at said plug during each ignition period, the intervals between reopenings of said primary circuit being each greater than the alternation period of the current of said source.

45 6. In an ignition system the combination of inductively related primary and secondary circuits, a spark plug connected with the secondary circuit, a source of alternating current for the primary circuit, circuit controller mechanism for said primary circuit normally holding said circuit open, and means for causing a succession of operations of said circuit controller mechanism during each ignition period of the engine with which the spark plug is associated, each operation causing a short closure of the primary circuit and reopening thereof to cause induced current flow through the secondary circuit and said spark plug whereby a plurality of distinct sparks is caused at said spark plug during each ignition period, the intervals between reopenings of said primary circuit being each greater than the alternation period of the current of said source, and said closures before reopening being of sufficient duration to permit said circuit controller mechanism to come to rest.

50 7. In an ignition system, the combination

of inductively related primary and secondary circuits, a source of alternating current for said secondary circuit, a spark plug included in the secondary circuit, circuit controller mechanism for said primary circuit, means for effecting a succession of operations of said circuit controller mechanism during each ignition period of the engine with which the spark plug is associated, each operation involving a closure of the primary circuit and reopening thereof, the duration of said closures being of sufficient length to permit said circuit controller mechanism to come to rest before re-opening movement thereof, each reopening causing induced current flow through the secondary circuit and a spark at the spark plug.

8. In an ignition system for explosive engines, the combination of inductively related primary and secondary circuits, a source of alternating current for said primary circuit, means for closing said secondary circuit in seriatim through the spark plugs of the engine, circuit controller mechanism for said primary circuit, means for causing a series of interruptions of said primary circuit during each closure of the secondary circuit, the interruptions of each series being separated by time intervals greater than the alternation time interval of the current flow from said alternating current source.

9. In an ignition system for explosive engines, the combination of inductively related primary and secondary circuits, a source of alternating current for said primary circuit, a spark plug connected in the secondary circuit, means for closing said secondary circuit during each ignition period of the engine cylinder with which said spark plug is associated, circuit controller mechanism for said primary circuit, a cam member rotated in timed relationship with the alternation of the current from said alternating current source, and cam formations on said cam member adapted to cause a series of interruptions of said primary circuit

circuit during each closure of the secondary circuit whereby there will be induced current flow through said secondary circuit after each interruption of the primary circuit, the time intervals between said interruptions being different and each longer than the alternation period of the alternating current.

10. In an ignition system, the combination of inductively related primary and secondary circuits, a source of pulsating current for said primary circuit, a spark gap in said secondary circuit, means for periodically closing said secondary circuit, an actuating member driven in timed relationship with the pulsations of said pulsating current, and means controlled by said actuating member for causing a series of interruptions of said primary circuit during each closure period of the secondary circuit, the intervals between the interruptions of each series being longer than the pulsation period of said current flow.

11. In an ignition system, the combination of inductively related primary and secondary circuits, a source of pulsating current flow for said primary circuit, a spark gap in said secondary circuit, means for periodically closing said secondary circuit for the flow of induced current from the primary circuit, circuit controller mechanism for said primary circuit, an actuating member for said circuit controller mechanism driven in timed relationship with the pulsations of said pulsating current, and means for causing said actuating member to actuate said circuit controller mechanism to produce a series of interruptions of the primary circuit during each closure period of the secondary circuit, the time intervals between said interruptions being of different lengths and each being of greater length than the pulsation period of said pulsating current flow.

In witness whereof, I hereunto subscribe my name this 14th day of May A. D., 1924.

ALONZO HOWARD.
